UNITED STATES PATENT OFFICE

157,296

KITCHEN RANGE VENTILATING CANOPY OR SIMILAR ARTICLE

John H. Sonntag, Dallas, Tex., assignor to Robert B. Sonntag, Dallas, Tex.

Application April 19, 1948, Serial No. 145,818

Term of patent 14 years

(Cl. D81—25)

To all whom it may concern:

Be it known that I, John H. Sonntag, a citizen of the United States, residing at Dallas, in the county of Dallas and State of Texas, have invented a new, original, and ornamental Design for Kitchen Range Ventilating Canopy or Similar Article, of which the following is a specification, reference being had to the accompanying drawing, forming part thereof.

Figure 1 is a front perspective view of a kitchen range ventilating canopy or similar article, showing my new design.

I claim:

The ornamental design for a kitchen range ventilating canopy or similar article, as shown.

JOHN H. SONNTAG.
